United States Patent Office.

JOHN KOFFEND, OF APPLETON, WISCONSIN.

Letters Patent No. 78,293, dated May 26, 1868.

IMPROVEMENT IN PLOUGHS.

The Schedule referred to in these Letters Patent and making part of the same.

TO ALL WHOM IT MAY CONCERN:

Be it known that I, JOHN KOFFEND, of Appleton, in the county of Outagamie, and State of Wisconsin, have invented a new and useful Improvement in Ploughs; and I do hereby declare that the following is a full, clear, and exact description thereof, which will enable others skilled in the art to make and use the same, reference being had to the accompanying drawing, forming part of this specification, in which—

Figure 1 is a side view of the land-side and point of a plough to which my improvement has been attached.

Figure 2 is a top view of the same.

Similar letters of reference indicate like parts.

My invention has for its object to furnish an improved attachment for ploughs, by means of which the land-side of the plough may be adjusted to cause the plough to run deeper or shallower, according to the character of the soil to be ploughed, and which shall at the same time be simple in construction, cheap, easily adjusted, and readily applied to any plough, whether new or old; and it consists in the combination of an auxiliary, adjustable, pivoted land-side with the ordinary land-side of the plough, as hereinafter more fully described.

A is the land-side, and B is the point of an ordinary plough, to which the mould-board, handles, and other parts are attached, in the ordinary manner. C is a land-side, which I prefer to make broader than the ordinary land-side A, and which lies along and is pivoted at its forward end to the said land-side A, at or near the standard, by a bevelled-headed bolt, as shown in fig. 2, and in dotted lines in fig. 1. The land-side C is so attached to the land-side A, that its outer side may be flush with the land-side of the point and coulter, as shown in fig. 2. The rear part of the land-side C is connected to the rear part of the land-side A, by a screw, D, which passes through an inwardly-projecting ear or flange, e', formed upon the said land-side C, and its former end is swivelled to an inwardly-projecting ear or flange, a', formed upon the land-side A, directly beneath the ear or flange e', as shown in figs. 1 and 2. This is the construction I prefer for new ploughs; but in the case of old ploughs, it is generally more convenient to attach the adjustable land-side to the inner side of the ordinary land-side A, as shown at E, figs. 1 and 2. In this case the land-side E may be made narrower than the land-side A, to which it is pivoted at its forward end by a bolt and nut, and adjustably connected at its rear part by flanges or ears and a swivelled screw, in the manner hereinafter described with reference to the land-side C. If desired, the land-side C or E may be adjustably connected to the land side A, by means of a bolt and nut, said bolt passing through a slot in the land-side A, and through a hole in the land-side C or E, so as to clamp the said land-side securely in any position to which it may be adjusted, but I prefer the construction first described.

By this construction, by lowering or raising the rear part, or heel of the adjustable land-side, the relative direction of the point is slightly changed, said point being made to tend downward, more or less, thus enabling the plough to be adjusted according to the character of the soil to be ploughed.

Having thus described my invention, I claim as new, and desire to secure by Letters Patent—

The combination of a pivoted, adjustable, auxiliary land-side with the ordinary land-side of a plough, whether said auxiliary land-side be placed upon the outer or inner side of said ordinary land-side, substantially as herein shown and described, and for the purpose set forth.

JOHN KOFFEND.
